UNITED STATES PATENT OFFICE.

HARRY R. CLARAGE, OF KALAMAZOO, MICHIGAN.

EXHAUST FAN.

Application filed April 3, 1924. Serial No. 703,953.

To all whom it may concern:

Be it known that I, HARRY R. CLARAGE, a citizen of the United States, residing at the city and county of Kalamazoo, State of Michigan, have invented certain new and useful Improvements in Exhaust Fans, of which the following is a specification.

This invention relates to improvements in exhaust fans.

10 The main objects of this invention are:

First, to provide an improved exhaust fan which is of large capacity and of high efficiency relative to its size.

Second, to provide an improved exhaust fan which is not likely to become clogged or broken by the passage of sticks or the like therethrough, for instance, where the fan is employed as an exhaust or suction means for wood working machines and the like.

20 Third, to provide an improved exhaust fan having these advantages which is reversible, that is, the motor and inlet may be reversed as may be desired, and also the direction of discharge, without in any wise impairing the efficiency or adaptability of the fan.

Further objects, and objects relating to structural details, will definitely appear from the detailed description to follow.

30 I accomplish the objects of my invention by the devices and means described in the following specification. The invention is clearly defined and pointed out in the claims.

A structure which is a preferred embodiment of my invention is clearly illustrated in the accompanying drawing, forming a part of this application, in which:

Fig. I is a side elevation of my improved fan, the discharge pipe being partially broken away.

Fig. II is an enlarged detail vertical section on a line corresponding to line 2—2 of Fig. I.

Fig. III is an enlarged detail section on a line corresponding to line 3—3 of Fig. II showing details of the fan.

Fig. IV is a detail section on a line corresponding to line 4—4 of Figs. II and III, showing further details of the fan.

50 In the drawing similar reference characters refer to similar parts throughout the several views, and the sectional views are taken looking in the direction of the little arrows at the ends of the section lines.

55 Referring to the drawing, 1 represents the motor and 2 the driving or fan shaft.

I provide a housing comprising a main annular body member 3 having a discharge 4 to which the discharge conduit 5 is connected. This body member has opposed side 60 openings 6, the openings being of the same size. One of these side openings is closed by the side wall 7 and the other by the inlet member 8. The side wall 7 has a central opening 9 therein for the shaft 2. These 65 side members have, in the structure illustrated, integral pedestals 10.

The inlet member 8 has an inwardly expanding inlet 11, the curve of the inlet being Venturi-like, that is, it is formed with a 70 view of expanding the flow, thereby lowering the velocity and transforming a part of the velocity head to suction or static head. This increases the effective wheel 75 inlet diameter over that of the inlet conduit 12.

The wheel comprises a hub 13 having radially disposed arms 14 on which are mounted blades 15. These blades are ovately shaped, disposed with their smaller ends inwardly, their outer edges 16 being straight.

The outer ends of the blades are forwardly curved and the blades are provided with forwardly curved flanges 17 on their side edges, the flanges 17 merging into the edges of the 85 blade at the outer ends thereof and at points adjacent the inner ends thereof—see Figs. III and IV.

By thus forming the blades their capacity is increased and further they are strengthened so that backing plates are not required.

The fan thus constructed is uniform, that is, no backing plates are required and it may be used either as a right or left-hand fan merely by changing the inlets, and the discharge may be located where desired.

My improved fan is of very high efficiency and, as stated, the discharge may be adjusted as desired and the fan may be driven in either direction.

I have illustrated and described my improvements in a form which I have found very practical. I have not attempted to illustrate or describe various modifications or adaptations as I believe the disclosure made 105 will enable those skilled in the art to embody or adapt my improvements as may be desired.

Having thus described my invention, what I claim as new and desire to secure by Letters Patent, is:

1. In a fan, the combination of a housing

- comprising a main body member having a tangential discharge and opposed side openings, a side wall, an inlet member having an inwardly expanding inlet of Venturi-like curvature, said side wall and inlet members being interchangeably mounted in said side openings, a shaft disposed through said side wall, a fan wheel comprising a hub having arms, and ovately-shaped blades mounted on said arms with their smaller ends disposed inwardly, their outer ends being forwardly curved, their side edges having forwardly curved flanges, the ends of which merge into the ends of said blades both at the outer forwardly curved ends thereof and at points adjacent their inner ends.
- 5 3. In a fan, the combination of a housing, a fan wheel comprising arms, and ovately-shaped blades mounted on said arms with their smaller ends disposed inwardly, their outer ends being forwardly curved, their side edges having forwardly curved flanges, the ends of which merge into the ends of said blades both at the outer forwardly curved ends thereof and at points adjacent their inner ends.
- 10 2. In a fan, the combination of a housing provided with an inwardly expanding side inlet of Venturi-like curvature, a fan wheel comprising arms, and ovately-shaped blades mounted on said arms with their smaller
- 15 20

ends disposed inwardly, their outer ends being forwardly curved, their side edges having forwardly curved flanges, the ends of which merge into the ends of said blades both at the outer forwardly curved ends thereof and at points adjacent their inner ends.

3. In a fan, the combination of a housing, a fan wheel comprising arms, and ovately-shaped blades mounted on said arms with their smaller ends disposed inwardly, their outer ends being forwardly curved, their side edges having forwardly curved flanges, the ends of which merge into the ends of said blades both at the outer forwardly curved ends thereof and at points adjacent their inner ends.

In witness whereof I have hereunto set my hand.

HARRY R. CLARAGE.
